Inventor;
C. DEFFRIES

United States Patent Office.

COLEMAN DEFRIES, OF LONDON, ENGLAND.

Letters Patent No. 78,580, dated June 2, 1868.

IMPROVEMENT IN FOOT-LIGHTS FOR THEATRES.

The Schedule referred to in these Letters Patent and making part of the same.

TO ALL WHOM IT MAY CONCERN:

Be it known that I, COLEMAN DEFRIES, of the firm of Jonas Defries & Sons, of No. 147 Houndsditch, in the city of London, England, have invented an "Improved Foot-Light;" and I do hereby declare that the following is a full and exact description thereof, reference being had to the accompanying drawings, and to the letters of reference marked thereon—

Figure 1 of the drawings being a front elevation of one of the sections or divisions of my improved foot-light,

Figure 2 a cross-section of same at A B, fig. 1, and

Figure 3 showing detached a reducing-joint, by which the foot is connected with a flue, leading to the outside of the building—

Similar letters denoting similar parts at each of the figures respectively.

A indicates a cast or wrought-iron framing or body, forming two hollow tubes or chambers, *a a'*, and carrying in the front a sash, *b*, for the reception of a sheet or sheets of glass. This framing or body may be made in sections, of any desired length, but I find two-feet lengths very suitable.

The front of the hollow tube or vitiated-air chamber, *a*, is wrought or cast in the concave shape shown, fig. 2, or sloping backwards from the stage, at an angle regulated by the rake of this latter, and is coated or covered with any suitable reflector. This section is supported in the centre by the angle-iron or leg, *c*, and has at each end angle-irons or flanges, *d*, (see fig. 2,) by which the sections are screwed or otherwise fastened together, to form, in combination, the length of float desired.

Above the top of each section, or of the combined sections, I place a plate, *e*, leaving a space between the top of the body or box A and this plate, for the introduction of sand or other heat-isolating material, or I leave this space free, and pierce the plate *e* with holes, *e'*, and the top of the body A with holes, *e''*, (see fig. 2,) for the introduction and exit of a current of cold air, as indicated by the arrows. When these boxes or sections A are placed in their proper position, and combined to form a foot-light, the tubes or chambers *a a'* of one section will come in a line with those of the preceding and succeeding sections, and, their ends being open, two continuous tubes or chambers will be formed in the entire length of the float.

The top of the float rises from three to four inches above the rake of the stage, which, at about a foot from the float, is cut sloping down to the level of the bottom of the chamber *a*, (see fig. 2.)

B indicates the main gas-pipe, passing beneath the stage from one side to the other, and *f*, branch-pipes, with burners rising within the frame formed by the front of *a* and the glass in *b*. Six of these burners are shown at fig. 1, but their number will vary with the length of the section, and other considerations.

It will be observed that each alternate burner is of the same height, and that each succeeding one is of a different elevation; also, that I bend my branch-pipes backwards, following the line of the concave reflector; but the branches might rise in a straight line from the gas-pipe B, although I deem it less convenient. The tap, *g*, of each burner, is placed near the junction of the pipes *f* and B, in order that they may, if desired, be easily reached from beneath the stage. The glass in front of the burners may rise to the top of the frame *b*; and air be supplied to the burners through an opening left between the top of the frame *b* and the top plate *e*; or the glass may rise only to within an inch or two of the top of the frame *b*, as may be desired. The burners are also supplied with oxygen through the open bottom, *h*. *i* indicates the bottom line of the reflector, which may be enamelled on the wrought or cast-iron frame or body A, or be a separate piece, made of any material commonly used for reflecting light. *j* indicates slits or openings, through which the vitiated air is drawn into the tube *a*, and *k*, fig. 2, indicates an opening, (of which there are several to each section,) by which the vitiated air passes from *a* to *a'*.

I would here observe, that although I have shown on the drawing two chambers or tubes for vitiated air,

in many cases α will be sufficient of itself to carry off the heated air, but in such case the angle-iron or leg c will be made longer, and of the shape most convenient for the fixing of the apparatus.

C, fig. 1, indicates the position of a reducing-piece, shown separately at fig. 3, by which the chamber α' is connected to an iron flue-pipe, C', in communication with the outer air. F, gas-burner, for creating a current of air when the float is first lit up. Instead of an iron flue-pipe, a brick one will be built where desirable, or an existing flue be used, the shape of the joint C being altered to suit the special requirements of the locality.

If only one vitiated-air chamber be used, the joint or reducing-piece C will be connected at one end to the end of the chamber α at its bottom or side, and by the other end with the brick flue or iron pipe C', D D', figs. 1 and 2, are brackets, assisting in supporting the sections, and carrying at their lower ends, sockets l , in which is received an iron barrel-shaft, E, which revolves on the brackets D, in bearings indicated by m , fig. 2. n are set-screws, for securing the shaft E in the sockets l .

At each of the brackets D D', and at each section throughout the full length of the float, the shaft E carries a grooved roller, over which passes the endless chain o , carried, also, on the pulley p , at the top of the body or frame A.

q q' are metal tubes, attached to the endless chains, and carrying the tammy-colored glass mediums or other material, r r' , fig. 2, by which colored light is thrown over the stage. The shaft E passes through the sockets l from side to side of the stage, as do the tubes q q' .

Instead of being raised and lowered by an endless chain, as shown, the mediums might ride in grooved uprights, each medium lifting by a separate chain or cord, like a window in its sash, but I prefer the arrangement shown.

The shaft E carries a fly at one end, and a grooved pulley at the other, this latter carrying a band, passing to a driving-pulley driven by a crank in the prompter's box, or the driving-pulley may be over the middle of the shaft if the prompter's box be in the front centre of the stage.

Action and Advantages of my Improved Foot-Light.

The effect of having the burners f at an alternating height, as shown, is that the light from the highest row of jets is cast almost horizontally over the stage, while that from the lower row is thrown more vertically; the shape of the concave reflector assisting greatly in this disposition of the light, which disposition may be modified by varying the relative height of the two rows of jets, and the angle of the reflector, whether concave or a simple inclined plane. By covering the space between the top of the reflector and that of the sash b with talc, or analogous material, in lieu of the front of top plate e , I can throw a soft light vertically and still further prevent all shadow, but I am of opinion that the arrangement shown on the drawing will be found quite sufficient for this purpose.

The effect of my arrangement of air-chamber or chambers α and α' , in connection with the pipe or flue C', is as follows:

When the burners f are first lit up, that, F, fig. 3, is also lit, and establishes a draught which draws the vitiated air from the space between the reflector and the glass through the slits g into chamber α' , and so on through the reducing-joint to the flue C', (as indicated by the arrows.) As before stated, the hot air may be drawn directly from the chamber α to the shaft C', if it be found inconvenient to have two chambers. The coolness of the entire apparatus is further increased by the cold air sucked in through the orifices e' and e'' . By these means no hot or unwholesome air or vapor passes to the stage or auditorium, and the health and comfort of actors and audience are preserved.

The sheet or sheets of glass in the sash b are not only necessary to my system of ventilation, but they also do away with the possibility of the flame from the burners reaching the dress of the actor or actress, and permit the use of ordinary fish-tails in lieu of the expensive argand-burners hitherto used, no chimneys being required.

The simplicity and convenient working of my improved arrangement of colored mediums will be readily understood. The prompter, or other functionary, by turning a crank placed in his box, or at the side of the stage, in one direction, causes the endless chains o to revolve, and carry up in front of the float the medium q , that, q' , lowering, and by reversing the motion he causes that, q , to lower and q' to rise to the position shown, fig. 2 of the drawing, or to pass q and q' in front of the foot-lights. This may be done by separate chains or ropes, and the mediums rise in an upright frame, grooved like a window-sash, but the arrangement shown I deem most simple and expeditious.

Having thus described the nature of my said invention, and the means by which I carry it into practical effect, I would have it understood that I do not confine myself to the use of any particular material, or to any precise dimensions of parts in the construction of my improved foot-light, nor to any size of float, varying the same, as may be found most suitable to the circumstances of each particular case, and although I prefer making my float in sections of two feet or thereabout, as being more handy for removal and fitting, nevertheless I may make the entire float of sheet iron, and build it on the spot, and whether made in sections of wrought or of cast iron, or built up on the spot, there may be either one or two chambers or vitiated-air conduits, as may be found most suited to the locality; neither do I absolutely confine myself to the use of an endless chain for raising or lowering the mediums, as shown on the drawing, as this may also be done by separate cords or chains raising the mediums in grooved uprights, and other modifications may be made in my improved foot-light without substantially departing from the principle of its construction.

I do not claim the exclusive use of any of the parts of my improved foot-light taken as parts, and not used in combination or for the purposes of my invention; but

What I do claim, is—

The exclusive use of an improved foot-light, constructed and arranged substantially as herein described, and shown on the accompanying sheet of drawing, whether the mechanism for raising and lowering colored mediums be or be not applied thereto.

COLEMAN DEFRIES,
147 Houndsditch, London.
